UNITED STATES PATENT OFFICE.

IVAN SIMATIČ, OF COKEBURG, PENNSYLVANIA.

HORSESHOE.

1,263,135.

Specification of Letters Patent. Patented Apr. 16, 1918.

Application filed October 20, 1917. Serial No. 197,597.

To all whom it may concern:

Be it known that I, IVAN SIMATIČ, a subject of the King of Hungary, residing at Cokeburg, in the county of Washington and 5 State of Pennsylvania, have invented certain new and useful Improvements in Horseshoes, of which the following is a specification.

The primary object of the invention is the provision of a horseshoe that can be 10 readily applied to a hoof and removed at will without the use of the usual nails, the shoe possessing great strength and being arranged for use when operatively attached to the hoof.

15 A further object of the invention is the provision of a special manner of hingedly connecting the side portions of a horseshoe forming a hinge joint between the portions of the shoe, not depending for its strength 20 upon the pivoting member with which the joint is provided.

In the drawing forming a part of this application and in which like designating characters refer to corresponding parts 25 throughout the several views,

Figure 1 is a top plan view of the device.

Fig. 2 is a sectional view thereof taken upon line II—II of Fig. 1.

Fig. 3 is a horizontal sectional view 30 through the hinged joint when closed.

Fig. 4 is a view thereof with the parts open, and

Figs. 5 and 6 are perspective views of the joint forming end portions of the side sections of the shoe.

It being understood that the device is designed to provide a shoe for animals such as a horse and one that can be readily attached and detached from the hoof without nails, 10 the same broadly consists of a shoe 10 having an arched base or shoe proper 11 for supporting the hoof of the animal, suitable calks 12 being arranged beneath the base 11 and an upwardly extending inturned 15 marginal flange 13 being carried by the upper side of the base. An extension 14 is provided for the toe portion 15 of the flange 13 adapted to overlie the forward portion of the hoof and arranged with a perforation 16 therein adapted for receiving a strap or 20 other suitable member, not shown, for assisting in retaining the shoe upon the hoof.

One side of the device is arranged with a hinged joint 17 substantially midway between the toe 15 of the shoe and the heel 18 thereof forming a swinging end section 19

hinged to the adjacent portion or side section 20 thereof. The hinged joint 17 is of special construction designed for bringing the strain incident to the operation of the 60 device mainly against the inner engaging ends 21 and 22 of the base 11 instead of bringing the strain upon the hinge pin or pintle 23 of the joint 17.

The ends 24 and 25 of the flange 13 at 65 the joining ends of the shoe sections 19 and 20 respectively are in the form of a hinge having the slot 26 of the end 24 adapted to receive the lug 27 of the end 25 while the pintle 23 passes through perforations 28 in 70 the end 24 at opposite sides of the slot 26 and also through an elongated opening 29 obliquely arranged through the lug 27. The base end 22 is arranged with a V-shaped tooth 32 adapted for reception within the 75 notch 30 when the hinge is closed, and a V-shaped tooth 33 may be arranged at the inner edge of the base end 22 for positioning adjacent the end face 34 of the finger 31 when the joint is closed.

80 Clamp connections 35 are arranged between the heel portions 18 of the shoe consisting of swiveled blocks 36 mounted upon the heels 18 and with a tubular socket 37 secured to one of the said blocks 36 and a 85 turn-screw 38 freely passing through the other block 36 and threaded within the socket 37. By turning the head 39 of the screw 38, the section 19 may be forced inwardly toward the opposite side of the shoe 90 when the joint 17 is partially open, while turning the screw 38 in the opposite direction releases the heel portions 18, permitting the section 19 to be swung outwardly 95 away from the opposite side of the shoe. In applying the device to an animal's hoof, the screw 38 is moved upwardly of or supported from the socket 37 sufficiently to permit the hoof to be positioned upon the base 11 with the flange 13 overlying the 100 sides of the hoof. The position of the ends 21 and 22 of the base 11 when the joint 17 is open is best shown in Fig. 4 of the drawing; and on the shoe being applied to the hoof as described, the screw 38 is turned 105 for drawing the heel portions 18 together, thereby moving the tooth 32 inwardly of the notch 30 upon the inner face 40 of the finger 31 and with the pintle 23 at the inner end of the perforation 29, the inward 110 swinging movement of the section 19 bringing the parts into their respective relations

best illustrated in Fig. 3 of the drawing. When the joint 17 is closed as shown in Fig. 3, the pintle 23 will be centrally arranged within the perforation 29 as also noted in Figs. 2 and 3 of the drawing, while the strain of travel is not upon the pintle 23 but substantially entirely upon the interengaging ends 21 and 22 of the base 11 forming a part of the joint 17.

10 A strong and serviceable horseshoe is arranged for ready attachment to the hoof of an animal, a joint portion of the shoe rendering the operation possible, while the joint possesses great strength when the device is in operation.

15 What I claim as new is:—

1. A device of the class described comprising a horseshoe having a hoof-supporting base, an upwardly and inwardly projecting hoof-positioning flange carried by the outer edge of the base, the said base and flange being severed at one side of the shoe forming slot and lug hinge members at the adjacent ends of the flange portions with perforations through the flange end at opposite sides of the slot adapted to align with an oblique elongated perforation arranged through the said lug, a pintle positioned through the said perforations,

and interengaging end portions for said base.

2. A device of the class described comprising a horseshoe having a hoof-supporting base, an upwardly and inwardly projecting hoof-positioning flange carried by the outer edge of the base, the said base and flange being severed at one side of the shoe forming slot and lug hinge members at the adjacent ends of the flange portions with perforations through the flange end at opposite sides of the slot adapted to align with an oblique elongated perforation arranged through the said lug, a pintle positioned through the said perforations, the said severing of the base forming a notch in the end of the base adjacent the slotted end of the flange and with a projecting finger at the inner side of the base adjacent the notch and also providing teeth upon the adjacent end of the other portion of the base, one of said teeth engaging within the said notch and the other positioned adjacent the free end of the finger when the joint is closed with the device in its operative arrangement.

55 In testimony whereof I affix my signature.

IVAN SIMATIĆ.
